ATTORNEY

UNITED STATES PATENT OFFICE

163,281

BALL GAME DEVICE OR SIMILAR ARTICLE

John R. Haupenthal, Los Angeles, Calif.

Application March 17, 1949, Serial No. 1,448

Term of patent 3½ years

(Cl. D34—5)

To all whom it may concern:

Be it known that I, John R. Haupenthal, a citizen of the United States, residing in the city of Los Angeles, in the county of Los Angeles, and State of California, have invented a new, original, and ornamental Design for a Ball Game Device or Similar Article, of which the following is a specification, reference being had to the accompanying drawing, forming a part thereof.

Fig. 1 is a top plan view of the ball game device or similar article, showing my new design; and

Fig. 2 is a sectional view thereof taken on lines 2—2 in Fig. 1.

I claim:

The ornamental design for a ball game device or similar article, as shown.

JOHN R. HAUPENTHAL.
